(57) **CLAIM**

The ornamental design for a cambering vehicle having a trellis design, as shown and described.

DESCRIPTION

FIG. 1 is a perspective view of a cambering vehicle showing my new trellis design;

FIG. 2 is a left side elevational view;

FIG. 3 is a frontal elevational view; and,

FIG. 4 is top plan view.

The broken lines shown in FIGS. 1-4 are for illustrative purposes only and form no part of the claimed design.
